WEB TENSIONING DEVICE

George L. Bezold, Hamilton, Ohio, assignor to
 The Hamilton Autographic Register Company,
 Hamilton, Ohio, a corporation of Ohio

Application February 3, 1934, Serial No. 709,656

10 Claims. (Cl. 197—133)

This invention relates to a device for typewriting machines utilizing continuous length stationery. In this class of typewriting machines the typing unit travels upon rails over a flat platen 5 upon which the stationery is held. The continuous length stationery, usually in a plural number of compiled strips, is either roll wound or packaged flat by zigzag folding, from which supply pack it is withdrawn and fed over the 10 platen of the typewriting machine presenting several strips in superposed arrangement, and above the platen is interleaved with manifolding or carbon sheets or strips for making manifold copies of the typing.

15 The strip stationery usually is provided with punchings, folding or tear lines in the spacing between the forms pre-printed upon the strips, or defining prescribed sheet lengths into which the strip is divided and which are used for gauging the foremost form or sheet length of the several 20 superposed strips appropriately upon the platen and in relative registration. The forward end of the platen carries pins or other anchoring means for engaging and holding the paper. When 25 pins are employed they engage through the punchings in the strip, anchoring the forward end upon the platen so that a rearward tension can be applied to the strip for tautly bringing the same over the platen.

30 The present invention is directed to a tension device for each web or strip employed, located in rear of the writing platen of the typewriting machine and preferably between the rear extensions of the rails translatable supporting the typ- 35 ing carriage, to apply and maintain a yielding rearward pull or tension upon the webs to smooth out an tautly present the same upon or over the writing platen.

An object of the invention is to provide a tension device for continuous length stationery in a typewriting machine for guidingly sustaining the stationery in edge alignment with the platen of the writing machine, and for exerting a yielding tension or back pull thereon to smooth out and 45 tautly present the paper upon the writing platen and constantly maintain the same in such condition while typing thereon.

Another object of the invention is to provide a device for applying tension to a web or continuous length of stationery to hold the same 50 tautly over a platen and comprising a pair of parallel rods for grippingly engaging the web therebetween, and as a unit translatable mounted and under tension in one direction to apply a yielding pull upon the webs, one of the rods rotat-

able or swivelled for contact with the other to impinge the web therebetween, and separable therefrom by rotating the same resulting from translating the device in a counterwise direction.

Other objects and advantages of the invention will be more fully set forth in the description of the accompanying drawings in which:

Figure 1 is a diagrammatic side elevation of a commercial typewriting machine within which the tensioning apparatus of the present invention 10 is installed, preferably within the rear rail extension thereof.

Figure 2 is a central longitudinal section through the improved web tension applying apparatus for handling a group or a plurality of 15 continuous lengths paper webs or strips and mounted within the rearward rail extension of a typewriting machine.

Figure 3 is a top plan view thereof.

Figure 4 is a section on line 4—4, Figure 3.

Figure 5 is a section similar to Figure 2, but illustrating the actuated parts in an adjusted position for releasing the webs or strips so that they can, with freedom, be advanced or adjusted.

Figure 6 is an enlarged sectional view of a portion of the apparatus with the parts adjusted as shown in Figure 5 and taken on a line 6—6, Figure 3.

Figure 7 is a central section of the apparatus with a section raised to a vertically inclined position for loading.

Figure 8 is a fragmentary plan view of the apparatus threaded with webs or strips of different width and one edge of one of the strips guided by a guide collar adjustably fixed upon 35 one of the strip gripping rods of a tension unit.

Figure 9 is a section on line 9—9, Figure 8.

Figure 10 is an enlarged plan view of one set of strip gripping rods for a tension unit; and

Figure 11 is a detailed section taken on line 40 11—11, Figure 10.

Referring to the drawings, and to Figure 1 thereof, diagrammatically disclosing a commercial typewriting machine of the class to which the present invention is applicable, 1 indicates a 45 frame or pedestal upon which the typewriting machine in general comprises a pair of horizontally disposed rails 2, upon which the typewriting unit 3 travels. A stationary printing platen or table 50 is fixed appropriately to the frame between the rails and extends within a forward section thereof. 4 indicates a reel or feeding device for the carbon or manifolding paper strips mounted alongside the rail 2, and 5 a table or shelf. 55

The rear sections of the rails are connected together, by several cross connecting rods 6 suitably spaced, which provide supports for sustaining the web or strip guiding and tensioning device of the present invention.

The device is arranged to be conveniently installed between the rearward extension of the rails and the operative parts connected with a foot treadle of the typewriting machine. The device consists of a pair of spaced side walls or bars 7, 7, rigidly connected at their opposite longitudinal ends by cross rods 8, 8, to form a rectangular frame as the main or outer frame of the device. The edges of the side walls at their opposite ends are notched for interlockingly engaging with the cross connecting rods of the rails of the typewriting machine. The outer frame of the device thus seats or rests upon the cross rods of the rails.

10 The side walls 7, 7, of the main frame, each is provided with a downwardly depending arm or bracket 9 rigidly fixed in place, the pair forming journals for rotatively supporting a supply roll of stationery. The lower ends of the bracket 15 arms are suitably notched for removably receiving and journaling a spindle 10 of the supply roll of stationery. The framing, however, may if desired, be provided with additional roll supporting brackets.

20 As shown in the drawings, some of the stationery is roll wound, while other is flat packed and taken as used from a carton in which the stationery is originally packed for storage and shipment.

25 A second or inner frame is hingedly mounted within the main or outer frame and comprises a pair of spaced sheet metal side walls 11, 11, connected at their opposite longitudinal ends by cross rods 12, 12, to provide a rigid rectangular frame structure.

30 This second or inner frame at its forward end is pivotally secured to the main frame, adapting the same to be swung upwardly from its normal horizontal position within the main frame, as shown in Figure 5, to an upright or vertical position as shown in Figure 7 for loading. Its upward swing is limited by stop pins 13 extending inwardly from the inner side of the side walls of the main frame and when in its horizontal position within the main frame rests upon pins 14 extending laterally or inwardly from the inner side of the side walls of the main frame, or from the depending brackets.

35 The inner frame hingedly carries a series of 55 cooperating cross rods or bars, one set for each of the number of strips of stationery employed and, as illustrated, the device is equipped for handling ten strips. The number, however, is optional, depending upon the capacity required.

40 A separate and independent set of rods is employed for guiding and tensioning each strip of stationery, although unitarily and simultaneously controlled to free the strips when required to adjust or advance the same. As the tensioning 45 means for each strip are of duplicate construction, the description thereof as to specific detail 50 will only be directed to one set.

55 Each set, therefore, comprises a rigid or non-rotatable rod or bar 15 having its opposite ends 70 respectively engaged or fixed to the upper ends of a pair of arms or levers 16, each pivoted at its lower end to the outer side of a corresponding side wall 11 of the inner frame. The second rod or bar 17 is of segmental form in cross section 75 or of a contour to provide a flat or plane tan-

gential surface 18 adjacent and longitudinally parallel with the fixed rod 15 to engage therewith for gripping or impinging the strip when threaded therebetween. The second rod 17 at each of its opposite ends is provided with a pin-like extension each engaged through the upper or free end of one of the levers 16 to swivel or journal therein. The rod has its journal axis preferably eccentric or slightly offset and disposed at an elevation slightly above the plane 10 of the axis of the stationary or fixed rod, adapting the swiveled rod 17 to be normally urged by gravity into contact or engagement with the periphery of the fixed rod to bind or impinge the strip therebetween. The strip is threaded 15 upwardly between the rods and then extends forwardly over the swiveled rod and in a direction toward the writing table of the writing machine to which the forward end of the strip is fixed. Upon any advancing motion of the 20 paper or retarding influence of the rods thereupon, the traction of the strip upon the rod rotatively urges the rod in a direction increasing its grip or impinging hold upon the stationary and fixed rod. The eccentricity of the axis of 25 the swiveled rod or its peculiar contour, serves to off-balance the rod so that it will swing by gravity to engage or contact its tangential surface with the fixed rod.

30 Both of the rods, at their respective opposite ends, extend beyond or across the top edge of the side walls of the inner frame to contact therewith and stop or limit the oscillating stroke of the levers and the bars as a tension-applying unit. The levers and rods as a unit are retracted by a pair of springs 19, 19, one for each lever, each having one end fixed to the lever toward the upper end thereof and its opposite end to a corresponding side wall of the inner frame for applying a rearward tension to the 35 strip engaged between the rods for holding the same tautly upon or over the writing table or platen of the writing machine. As shown in Figure 4, the parts are in full retreat position at which the fixed rod contacts with the upper 40 edges of the side walls of the inner frame, limiting the retreat stroke of the levers and rearward traverse of the unit. The springs are positioned so that the tension is not unduly increased for the full arc of movement allowed, 45 thereby avoiding applying an excessive pressure or tension upon the strip which may strain or cause it to tear apart along a fold or tear-line between the writing or form spaces and at all times they impart or apply a tension sufficient to hold and maintain the sheet tautly 50 over the writing table.

55 The gripping or impinging contact of the rods can be positively released for freeing the strips to adjust or advance the same by moving the 60 tension unit forwardly toward the writing table, bringing the swiveled rod into contact or engagement with the top edges of the side walls of the inner frame. The opposite ends of the 65 swiveled rod which contact with the upper edges of the side walls of the frame are of cam formation or contour for rotating the rod upon its axis as it is brought to forcibly bear upon the upper edges of the side walls, swiveling the same, swinging its tangential face or flat portion away 70 from the fixed rod, spacing the rods to a degree sufficient to release or free the strip therebetween so that it can be unrestrictedly advanced or adjusted therethrough.

75 The tension units of a series are simultane-

ously translated in a counter direction controlling the swiveled rods of each unit for releasing the strip impingement, by a pair of rack bars 20, 20, respectively arranged at the opposite ends 5 of the rods along a row of levers 16 at a corresponding end of the rods.

A pair of rack bars are employed for equalizing purposes to uniformly move the tension units. Each rack bar at its opposite longitudinal ends 10 is pivotally connected to a respective link 21. The link 21 for one end of the rack bar is pivotally connected to a side wall of the inner frame, while the link for the opposite end of the rack bar is fixed to a rock shaft 22 journalled 15 in the side walls of the inner frame.

The rock shaft centrally of its length has a crank arm 23 fixed thereon, extending forwardly therefrom and pivotally attached to one end of a connecting rod 24. The opposite end of the 20 connecting rod 24 is pivotally connected at an intermediate point to a treadle lever 25 supported upon a pedestal of the typewriting machine as shown in Figure 1. Each rack bar is provided with a plurality of teeth or tongues 26, one for 25 each tension unit, appropriately spaced apart and extending upwardly from the upper longitudinal edge of the bar for engaging with a pin or lug 27 extending laterally from the inner side of a relative lever 16.

Upon depressing the foot treadle lever 25, the 30 rack bars 20 are unitarily shifted forward carrying the tension units therewith, slackening the strips. When the unit has been moved to engage the ends of the swiveled rod upon the upper edge 35 of the side walls of the inner frame the rod is rotated or swiveled moving its tangential surface away from the fixed rod, releasing the grip upon the strip. The strip can then be adjusted or advanced to bring a second form or sheet length 40 appropriately over and upon the writing platen for typing and issuing the previously typed foremost portion which is torn or severed from the sheet.

Upon releasing the treadle for a retreat of the 45 rack bars, the swiveled rod of the tension unit is again free to swivel or revolve and contact with its companion fixed rod moving by gravity and aided by the traction pull imposed thereon by the sheet which loops over the swivel roll in extending forward to the writing platen.

The tension units, under the action of the 50 springs in a retreating or receding stroke, draw the strip therewith until it becomes taut over the writing table to present a flat writing surface for making clear writing impression thereon, and 55 thereupon constantly maintained under tension.

To offer greater convenience and access for loading or threading the strips, each between a set of rods of the tension units, the inner frame being pivoted to the outer frame can be swung 60 upwardly to a vertical slightly reclining or inclined position as shown in Figure 7. In such position the balance of swiveled rods is changed so that they will swivel by gravity in a direction to bring the tangential surface of one rod away 65 from its respective companion rod, thereby automatically separating the rods and providing ample spacing therebetween for freedom of passage of the strip, and as soon as the frame is lowered the rods of each unit are automatically brought 70 together impinging or gripping the paper therebetween.

After such initial loading operation, the operator upon depressing the treadle immediately releases the strips for freely advancing or adjusting 75 the same over the writing platen and immediately

upon release of the treadle the strips are again gripped and tension applied thereon ready to proceed with the typing. It is obvious that the grip rods can be mounted to move in any horizontal line instead of an arc as resulting from mounting the rods at their opposite ends upon a pair of levers and the swiveled rod controlled by traction through its peripheral engagement with the top edges of the side walls. Likewise, the double frame structure can also be eliminated if 5 the tension units are directly built into the typewriter although as an attachment it is readily available in used typewriting machines.

It is also desirable that the strips be longitudinally guided to align the edges with the longitudinal edges of the platen or present the same in parallelism therewith and for handling various widths of stationery. For this purpose a pair of longitudinal guide strips 28, 28, are provided, positioned intermediate of the inner frame 10 and at their opposite longitudinal ends are adjustably secured to a pair of cross rods of the framing, the guide strips serving a group of paper strips of the same width. When the individual paper strips of a group are of relatively different 15 widths, each strip is individually guided by one or a plurality of guide collars 29 adjustably mounted upon the fixed rod of a tension unit as shown in Figures 8 and 9. The swiveled rod is 20 and at their opposite longitudinal ends are adjustably secured to a pair of cross rods of the framing, the guide strips serving a group of paper strips of the same width. When the individual paper strips of a group are of relatively different 25 widths, each strip is individually guided by one or a plurality of guide collars 29 adjustably mounted upon the fixed rod of a tension unit as shown in Figures 8 and 9. The swiveled rod is notched at intervals of its length to receive or 30 straddle a collar as is shown in Figure 11. The strips of a same or different width can be relatively off-set, one edge aligned with a longitudinal guide strip 28 and an opposite edge by a collar 29 on the fixed grip rod.

Having described my invention, I claim:

1. In a typewriting machine including a stationary platen and means located between a supply of continuous length stationery and said typewriter platen for applying tension to the paper engaged over the platen, comprising, a pair of parallel rods between which the paper web is threaded and engaged over one thereof for leading the web toward the platen, said leading rod swiveled for impinging the other and gripping the web therebetween and the impinging force augmented by the tractive action of the web upon said rod, said rods unitarily translatable toward and from the platen and yieldingly urged in a retreat direction for tensioning the paper.

2. In a typewriting machine including a stationary platen and means located between a supply of continuous length stationery and said typewriter platen for applying tension to the paper engaged over the platen, comprising, a frame, 40 and a pair of rods adjacently disposed between which the paper web from the supply to the platen is threaded, one of said rods journalled to swing by gravity toward the other and contact therewith for gripping the paper therebetween, 45 said rods carried by said frame and unitarily translatable toward and from the platen and yieldingly urged in a retreat direction for tensioning the paper over the platen and said frame shiftable to a position changing the center of gravity of said journalled rod for automatically swinging it to a retreat position away from the other rod for freedom in threading the web between said rods.

3. In a typewriting machine including a stationary platen and means located between a supply of continuous length stationery and said typewriter platen for applying tension to the paper engaged over the platen, comprising, a pair of parallel rods between which the paper web is 50

threaded and engaged over one thereof for leading the web toward the platen, said leading rod swiveled for impinging the other and gripping the web therebetween and the impinging force 5 augmented by the tractive action of the web upon said rod, said rods unitarily translatable toward and from the platen and yieldingly urged in a retreat direction for tensioning the paper, a stationary rail engageable by said leading rod, and 10 control means for translating said rods as a unit counter to its yielding retreat, engaging the leading rod upon said rail and by traction thereon swiveling said leading rod for separating the rods from contact with one another giving freedom 15 to the web.

4. In a typewriting machine including a stationary platen and means located between a supply of continuous length stationery and said typewriter platen for applying tension to the 20 paper engaged over the platen, comprising, a frame, a pair of rods adjacently disposed between which the paper web from the supply to the platen is threaded, one of said rods journaled to swing by gravity toward the other and contact 25 therewith for gripping the paper therebetween, said rods carried by said frame and unitarily translatable toward and from the platen and yieldingly urged in a retreat direction for tensioning the paper over the platen and said frame 30 shiftable to a position changing the center of gravity of said journaled rod for automatically swinging it to a retreat position away from the other rod for freedom in threading the web between said rods, and control means for translating said rods as a unit in a direction counter to its yielding retreat, engaging said journaled rod on an edge of said frame and by traction thereon 35 swiveling the same for separating the rods from contact with one another giving freedom to the 40 web.

5. In a typewriting machine including a stationary platen and means located between a supply of continuous length stationery and said typewriter platen for applying tension to the paper 45 engaged over the platen, comprising a pair of parallel rods between which the paper web is threaded and engaged over one thereof for leading the web toward the platen, said leading rod swiveled for impinging the other and gripping the 50 web therebetween and the impinging force augmented by the tractive action of the web upon said rod, said rods unitarily translatable toward and from the platen and yieldingly urged in a retreat direction for tensioning the paper, and 55 means for positively moving said rods as a unit in a direction toward the platen to slacken the web.

6. In a device of the nature disclosed for applying tension to a web of paper, a frame, a pair 60 of rods adjacently disposed to receive the web of paper therebetween, lever arms pivotally mounted on said frame for relatively supporting said rods in compressive contact to grip the web, and translate the same as a unit, one of said rods as 65 a strip leading rod eccentrically swiveled on said lever arms and engageable with an edge of said frame, means for yieldingly urging said lever arms and rods as a unit in a direction for applying and maintaining a tension on said web, and 70 a reciprocable bar mounted upon said frame remotely operable and connecting with said lever arms for moving said rods in a direction to slacken the web engaging said leading rod with an 75 edge of said frame and by traction thereon

swiveling the same to separate said rods for web freedom therebetween.

7. In a device of the nature disclosed for applying individually to a plurality of webs of paper from a supply source to a platen, the webs of the series presented in superposed arrangement upon the platen and at their forward end secured thereto, a tension unit for each web of the series comprising a pair of parallel rods between which the web is threaded and engaging over one thereof in a direction leading to the platen, one of said rods eccentrically pivoted and movable by gravity and by the tractive action of the web thereon into contact with the other for gripping the web therebetween, a rail engageable by 15 said eccentrically pivoted rod, each tension unit translatable toward and from the platen and yieldingly urged in a retreat direction for tensioning the web upon the platen and a single control means for all of the tension units of the 20 series for simultaneously moving the units in a direction to slacken the webs engaging said eccentrically pivoted rod against said rail and by traction thereon swiveling the rod for separating the rods of each respective unit from contact with 25 one another giving freedom to the webs.

8. In a device of the nature disclosed for applying individually to a plurality of webs of paper from a supply source to a platen, the webs of the series presented in superposed arrangement 30 upon the platen and at their forward end secured thereto, a frame for supporting a plurality of tension units, a tension unit for each web of the series comprising a pair of parallel rods between which the web is threaded and engaging over 35 one thereof in a direction leading to the platen, one of said rods eccentrically pivoted and movable by gravity and by the tractive action of the web thereon into contact with the other for gripping the web therebetween, each tension unit 40 translatable upon said frame toward and from the platen and yieldingly urged in a retreat direction for tensioning the web upon the platen, and a single control means for all of the tension units of the series for simultaneously moving the 45 units in a direction to slacken the webs engaging the eccentrically pivoted rods of each unit against an edge of the frame and by traction thereon swiveling the eccentrically pivoted rods each 50 away from contact with its companion rod for giving freedom to the webs, said frame hingedly mounted adapting the same to be swung to a position at which the leading rod of each tension unit will automatically move away from its companion rod.

9. In a typewriting machine, a platen over which strip stationery is adapted to be moved and means located between the supply of stationery and platen for applying tension to the portion of the stationery positioned over the 60 platen and held thereon at its forward end, comprising, a pair of rods between which the stationery passes and engages over one rod thereof for leading the stationery toward the platen, said rods mounted for unitary movement in an arc 65 toward and from the platen and yieldingly urged in a direction from the platen, said leading rod eccentrically journaled for swiveling under the traction pull of the stationery thereon induced by the yielding retreating force of said rods for 70 contacting with the other of said rods and gripping the stationery therebetween for applying a pull on the portion of the stationery on the platen of the typewriting machine.

10. In a typewriting machine, a platen over 75

which strip stationery is adapted to be moved and means located between the supply of stationery and platen for applying tension to the portion of the stationery positioned over the platen and held thereon at its forward end, comprising, a frame, a pair of rods between which the stationery passes and engages over one rod thereof for leading the stationery toward the platen, said rods mounted on said frame for unitary movement in an arc toward and from the platen and yieldingly urged in a retreat direction, said leading rod eccentrically journaled for swiveling

under the traction pull of the stationery thereon induced by the yielding retreating force of said rods for contacting said leading rod against its companion rod, gripping the stationery therebetween, and applying a pull on the portion of the stationery over the platen of the typewriting machine, said leading rod in a forward translation arranged for contact with an edge of the frame, and by traction thereon to be swiveled away from contact with its companion rod.

5
